STAMPING MACHINE AND THE LIKE

Leonard Nachemov, New York, N. Y., assignor to Abraham J. Sossner, Theodore T. Sossner, and Nettie Sossner, copartners doing business as Sossner Steel Stamps, New York, N. Y.

Application April 27, 1943, Serial No. 484,693

1 Claim. (Cl. 191—110)

The present invention relates to marking, stamping, embossing and similar machines and more particularly to the type where the matter to be stamped is easily changed and truly aligned.

An object of this invention is to provide a novel and improved machine of the type mentioned employing a series of wheels each having equi-spaced marking or embossing characters, as the letters of the alphabet, numerals or other insignia on the periphery thereof; each wheel being capable by a single means, of being revolved any required amount independently of the others, and all to be locked against rotary movement when characters composing the matter to be stamped or embossed, are presented in operating position.

Another object hereof is to provide a machine of the class set forth, of novel and improved construction where the wheel rotator is automatically shifted into true operating position with respect to any of the wheels, a little ahead of the operator's manual manipulation, whereby accuracy of operating position of said wheel rotator is assured independent of the operator's adjustment, and where the rotary movement of the wheel from character to character thereon into operating position is automatically shifted into true position, a little ahead of operator's manual manipulation, whereby accuracy of operating position of each wheel is assured independent of the operator's adjustment.

A further object is to provide a novel and improved machine of the character described where the depth of the embossing or amount of impression is controllable.

A further object hereof is to provide a machine of the class mentioned of novel and improved construction, adaptable for imbedding metal leaf into the impressions embossed on objects, as for instance the names on wood pencils or designs impressed on leather hat bands or gold leaf stampings on book covers or similar work.

Still another object of this invention is to provide a novel and improved machine of the nature described which is simple to set up and operate, compact, positive in action, and efficient in carrying out the purposes for which it is designed.

Other objects and advantages will become manifest as this disclosure proceeds.

In the accompanying drawings, forming part 50 of this application, similar characters of reference indicate corresponding parts in all the views.

Fig. 1 is a side view, partly in section, of an embodiment of this invention.

Fig. 2 is a section taken at line 2—2 in Fig. 1,

of the stamping device and the means employed to arrange the character carrying wheels into any desired relation in order to present in proper position and sequence, the characters constituting the matter to be stamped or embossed.

Fig. 3 is a perspective view of a component of the machine.

Fig. 4 is a plan view of Fig. 1, in reduced scale and partly fragmentary.

Fig. 5 is a fragmentary enlarged perspective view of the character bearing wheels employed in the embodiment set forth.

Fig. 6 is a side view of the middle portion illustrated in Fig. 1.

Fig. 7 is a side view of a portion of the machine of Fig. 1, at the left-hand side thereof.

In the drawings, the numeral 15, designates generally a casing for housing the stamping or embossing mechanism. A shaft 16, is slidably mounted through said housing and its ends protrude exteriorly therefrom. Said shaft 16, has a knob 17 at one end, and a head 18 at the other of its ends. The head 18 is housed within a hollow knob 19 of a tubular member 20. This member 20, is exteriorly threaded at 21, at which portion it is threadedly engaged with the casing 15. Member 20 is a sleeve on the shaft 16. The chamber 22, is of a dimension along the line of the shaft 16, to permit a comparatively short longitudinal movement of said shaft thru member 20; head 18 serving to limit such movement.

Said shaft 16, carries securely mounted thereon, a gear 23, and also the brackets 24 and 25, through which said shaft is rotatable. A plate 26, on which said brackets 24 and 25 are securely mounted, maintains said brackets, over at each side of the gear 23, and in contact with the latter, so that upon longitudinal movement of shaft 16, the plate 26 and the brackets 24 and 25 carried by said plate, are moved along with the gear 23.

A series of gear wheels 27, all of identical size and each having the same number of equi-spaced teeth, are carried on the tubular member 28, and each wheel is independently axially rotatable thereon.

Gear 23, is engageable with any of the wheels 27; with which, depending at any time on the position of the ends of shaft 16 with respect to the casing 15.

The numerals 29 and 30 indicate collars which preferably are of heat-insulative material; if it is desired to include a preferably electric heating coil 31 within the tube 28 for purposes herein-after explained, so that only the wheels 27 are

heated and the rest of the device substantially insulated from the effect of said heating means. The collars 29 and 30 are securely mounted within the casing 15 whereby the tube 28 is firmly positioned.

The peripheral surface of each tooth of each of the wheels 27, is an embossing or stamping element. For instance, each wheel 27 may have thirty-six teeth, so that the embossing or stamping elements would compose the complete alphabet and the numerals from zero to nine. Of course, said embossing or stamping element may be of any desired insignia or character. The respective aligned teeth of wheels 27, at position 51, comprise the matter to be embossed onto for instance a pencil 32, positioned on V block 33, carried by member 34, the arm 35 of which is pivotally mounted at 36 on frame 37. Said member 34 is raised or lowered with respect to said teeth at position 51, by means of a cam 38 rotatably mounted on shaft 39, operated by a handle 40.

Plate 26, lies across all the wheels 27, between two rows of aligned teeth, thereby locking the wheels 27, to maintain at position 51 the row of teeth comprising the matter desired to be embossed on pencils 32; one of the latter at a time. The cross section of said plate 26, along its edge, between said rows of teeth of wheels 27, being that of one of said teeth. Of course the position 30 of gear 23, by movement of shaft 16, at such set up, being away from said wheels 27.

Plate 26 is slidably supported on channel 41 which is fixed to the casing 15 on shelf 42, the latter holding a steel ball 43 positioned in and through a hole therein as a socket for said ball. A blade spring 44 mounted on the shelf 42, maintaining said ball 43, against the plate 26 and is adapted to enter the respective holes 45 successively of the series drilled in said plate; the distance between said holes 45 being the thickness of a wheel 27.

The gear 23 also has a series of holes 46, arranged in a circle and spaced as are the teeth 47 of said gear 23. A steel ball 48, housed in bore 49 maintains said steel ball 48 against the gear 23. On the periphery of the wheels 27 between the teeth thereof, is marked a character corresponding to the embossing element on the particular wheel 27 at operative position 51. An indicator 52 mounted on bracket 25 and hence travelling therewith, points to such marking.

Should it be desired to imbed metal foil in the embossed characters, the following may be provided.

A roll 53 of metal leaf material is mounted on shaft 54 held in bracket 55 on the casing, against which roll, acts a blade spring 56 with slight friction throughout. Said ribbon leaf material passes under idler rollers or guides 57 and 58 and between the series of wheels 27 and the V block 33, and thence between a pair of rollers 60 and 61 mounted on a bracket 62 and maintained in frictional contact by means of the coil springs 63, the ends of which are secured to the paired ends of the shafts of said rollers 60 and 61.

Roller 61 carries a ratchet wheel 64 on its shaft 65 adapted to be shifted a little when the blade or pawl 66, adapted to engage with the teeth of said ratchet wheel, every time arm 67 of bell crank lever 68 pivotally mounted at 69, is shifted downward by pin 70 extending from cam 38. Said arm 67 is restored to upward rest position by spring 71.

To regulate depth of embossing impression on object 32, its holder 34 may be raised or lowered by means of a wedge 72 slidably mounted on 73, and its movement effected by means of screw 74 threadly engaging wedge 72; the end of said screw 74 being swivelly mounted to member 73 at 75. Upon making the desired adjustments of wedge position, screw 74 is locked against movement, by means of a handled lock nut 76 thereon.

10 The boss 71 of holder 73, is slidably mounted for vertical movement between the guides 78, and is maintained against the wedge 72 by means of the series of springs 79 in holes 80, plugged by screws 81.

In operation as a stamping machine, meaning without the use of the ribbon member 53 and its motivating mechanism, the cam 38 is positioned whereby holder 34, due to its weight, is in lowered position.

20 Gear 23 is at the left interior casing 15 in Fig. 2, out of contact with any of the wheels 27. Steel ball 43 is engaged in the first hole 45. Stop element 18 is in contact with member 83 of hollow knob 19; the distance between the centers of the hole 45 and the first of the holes 45 nearest it, and the distance between any other pair of consecutive holes 45 being equal to its thickness of a wheel 27. Plate 26 engages all the wheels 27 and maintains them against rotary movement.

25 The steel ball 43 is in engagement with the body of the gear 23 in one of the holes 49. The wheels 27 are now to be respectively consecutively set so that their respective characters presented at position 51 comprise the matter to be stamped on to object 32, a pencil in the example here illustrated.

30 Knob 19 is now taken in hand and turned counterclockwise, whereby sleeve 20 will slide free on shaft 16 until stop element 18 is against wall 44 of chamber 22. Further movement of knob 19 in the same rotary direction will cause shaft 16 to be slid to the right. The ball 43 will leave a hole 45 and upon approaching the first newest hole 45, will be caused by action of spring 50 to automatically shift into said first hole 45, causing shaft 16 to automatically shift to the right a little ahead of what would be its normal movement due to its being pulled along by knob 19; stop member 18 having space along the horizontal within chamber 22 for such automatic accelerated shift of shaft 16 along axis line.

35 Upon entrance of said ball 48 into the first hole 49, which is opponent to the operator's feel and is accompanied by an audible "click," knob 19 is let go. Gear 23 is now in engagement with the teeth of the first wheel 27 at the extreme left of the casing 15 and said first wheel 27 is free of restraint by plate 26 because said wheel is free thru slot 66 in plate 26 which slot is co-planar with gear 23. The operator, by observing the notations by aid of indicator 52, and by turning knob 17, will thereby cause gear 23 to turn said first wheel 27 an amount so that the required first character is in position 31. The action of spring 50 on ball 48, as gear 23 is rotated, will be to automatically urge the operator to accelerate the rotary movement of knob 17, for said ball is strongly urged into engagement with the succeeding hole 49. It is to be noted that when ball 43 is in any of the holes 45, gear 23 is in true co-planar alignment and full engagement with one of the wheels 27, and that when ball 48 is in any of the holes 49, a tooth of such engaged wheel 27 is in true operating position 31.

40 45 50 55 60 65 70 75 When the required character of the first wheel

27 is in position 31, the knob 19 is again turned counterclockwise to bring gear 23 into engagement with the next wheel 27 and then knob 17 is again operated, subject to like incident as explained, as is evident to set all the wheels 27, so that in aggregate, their teeth presented at position 31 comprise the matter to be stamped onto the object 32.

It is important to note that all the wheels 27, are locked against rotary movement by plate 26, except the particular wheel 27 which is aligned and in engagement with the gear 23. After all the wheels 27 have been properly arranged, gear 23 is returned to the extreme left rest position out of contact with any of the wheels 27, in which position, all of said wheels 27 will be locked by the plate 26.

By operating handle 40, cam 38, will raise holder 34, and cause an impression of the stamping or embossing characters at position 31, onto the object 32. Return of handle 40, to initial position, will cause holder 34 to fall, and object 32, can now be removed and replaced by another for repetition of the cycle of operation. The depth of impression can be regulated by adjustment of position of wedge 12, to lower or raise the holder 34, and thus initially set same.

The ribbon member 53 may carry an inking substance or, metal foil for "inlay" into the embossed characters, aided by heat aforementioned, or for gold stamping where the characters are printing type. The operation of the feeding mechanism of such ribbon member 53, is effected upon movement of bell crank 68, caused by pin 70 in its travel with cam 38, once during each cycle, whereby pawl 66 will cause a slight rotary movement of rollers 60 and 61, to present a "fresh" portion of said ribbon at operating position 31.

This invention is capable of various forms and numerous applications without departing from the essential features herein disclosed. It is therefore intended and desired that the embodiment set forth herein be deemed illustrative and not restrictive, and that the patent shall cover all patentable novelty taught herein; reference being had to the following claim rather than to the specific description herein to indicate the scope of this invention.

I claim:

In a machine of the character described, the combination of a frame, a shaft mounted on the frame, a series of gear wheels carried on the shaft loosely for rotation thereon; said wheels having an identical number of teeth and teeth of each wheel having characters thereon from which an impression can be made, a driving gear mounted slidably along its axis on the frame; said driving gear being adapted to be positioned in engagement with any of said wheels of the series one at a time whereby each of the wheels of said series is individually turnable whereby a selected tooth on same present in sequence characters in alignment composing the matter to be impressed, a plate member slidable with the driving gear, adapted to lie between aligned rows of successive teeth respectively of said wheels whereby said wheels are locked against rotation; said plate member having a slot co-planar with the driving gear through which slot the particular wheel in engagement with the driving gear is free to revolve unrestrained by the plate member; the driving gear being provided with a series of sockets arranged in a circle thereon; the spacing of said sockets being as the spacing of the teeth of said driving gear, a rotatable shaft slidably mounted on the frame in parallel relation with the shaft carrying the wheels, a bracket carried on said rotatable slidable shaft; the plate member being secured to the bracket and the driving gear being securely carried on said rotatable slidable shaft, a spring mounted on the bracket, a ball positioned between spring and driving gear and in contact with said driving gear along the line of the sockets; the spring being adapted to maintain the ball against said driving gear and said ball being adapted to engage said driving gear in the respective sockets consecutively upon movement of said driving gear about its axis upon rotation of said rotatable shaft, to assure proper movement of the wheel engaged by the driving gear the distance of one tooth of said wheel and whereby upon approach of a socket to the ball, movement of the driving gear is automatically accelerated by action of the spring in shifting the ball into the approaching socket.
